INVENTOR
JULIUS R. BUX,
BY Louis Necho
ATTORNEY

UNITED STATES PATENT OFFICE

109,390

DESIGN FOR A SLIDE FASTENER TAPE

Julius R. Bux, Melrose Park, Pa., assignor to J. Sullivan & Sons Mfg. Co., Philadelphia, Pa., a corporation of Pennsylvania

Application January 12, 1938, Serial No. 74,220

Term of patent 7 years

To all whom it may concern:

Be it known that I, Julius R. Bux, a citizen of the United States of America, residing at Melrose Park, in the county of Montgomery and State of Pennsylvania, have invented a new, original, and ornamental Design for a Slide Fastener Tape, of which the following is a specification, reference being had to the accompanying drawing, forming part thereof, in which:

Fig. 1 is a plan view of a portion of the tape showing my new design; and

Fig. 2 is an end view of the disclosure in Fig. 1.

I claim:

The ornamental design for a slide fastener tape, as shown.

JULIUS R. BUXT
